UNITED STATES PATENT OFFICE.

WILLIAM R. KINNEAR, OF COLUMBUS, OHIO.

FIREPROOF SHUTTER.

SPECIFICATION forming part of Letters Patent No. 546,857, dated September 24, 1895.

Application filed December 7, 1894. Serial No. 531,119. (No model.)

To all whom it may concern:

Be it known that I, WILLIAM R. KINNEAR, a citizen of the United States, residing at Columbus, in the county of Franklin and State 5 of Ohio, have invented certain new and useful Improvements in Fireproof Shutters; and I do hereby declare the following to be a full, clear, and exact description of the invention, such as will enable others skilled in the art 10 to which it appertains to make and use the same.

The object of my invention is to provide improvements in the construction of fireproof shutters, doors, and the like. It is desirable 15 that such shutters, doors, and the like be as light as possible, and to attain this it is essential to employ more or less wood or other light material in the construction of the frames. This frame is protected from combustion by a sheathing of sheet metal, and to prevent the opening of the seams from warping of the metal, due to the contraction and expansion thereof, and especially when exposed to violent heat, is the chief object of my 20 present invention. This feature, as well as the remaining features of my invention, are illustrated in the accompanying drawings, in which—

Figure 1 illustrates in elevation a part of a 25 shutter, a portion of the panel being broken away to illustrate the interior construction. Fig. 2 is a sectional view taken on line $\alpha\alpha$ of Fig. 1. Fig. 3 is a sectional view on the line $\gamma\gamma$ of Fig. 1. Fig. 4 illustrates a sectional 35 view on a larger scale to better illustrate the details of the chief feature of my improvements.

The character 1 designates the wooden frame, which is of the usual rectangular form 40 and is made with a saw kerf or groove 2 at its inner side. In this groove I place a strip of metal 3, preferably hard. A sheathing of metal 4 covers the frame and is secured thereto by nails driven into the wood and against the 45 metal strip, so that their points shall be turned aside and thereby clinched.

The cross-pieces 8, extending between the vertical sides of the shutter-frame, are preferably composed of two pieces of wood with 50 a metal clinching-strip 3 laid between them. In order to protect these cross-pieces against charring or combustion, they are covered with a protective sheathing of metal, as shown. The panels 5, of proper contour and orna- 55 ments with any suitable design, are next se-

ctured to the frame, their edges being held by nails 6, driven into the wood and against the metal strip 3 and clinched, as shown.

In order to render the shutters or doors more perfectly fireproof, I propose to fill the space 60 between the panels with asbestos or other poor conductor of heat or with some non-combustible material. This material may be retained in position by a number of zigzagged strips of metal 9, laid vertically within the 65 space, as shown. To prevent the panels from bulging when exposed to heat, I employ a number of rivets 10, secured between them at proper intervals. These rivets also assist in retaining the asbestos in position. The metal 70 nail-clinching strip is also employed at the miter-joints of the frame, as indicated at the corners of the frame.

It will be seen that the present improvements secure lightness, durability, and fire- 75 proofness without any sacrifice of comeliness in the appearance of shutters, doors, and similar structures.

What I claim, and desire to secure by Letters Patent, is—

1. In fire-proof shutters and the like, a 80 frame, panels secured to said frame, a fire-proof packing in the space between said panels, with devices substantially as described for retaining said packing in position.

2. In fire-proof shutters and the like, a 85 frame, panels secured to said frame, a fire-proof packing in the space between said panels, devices for retaining said packing in position, and rivets uniting the panels, substan- 90 tially as shown.

3. A body of wood or similar material, a 95 hard strip placed within said material, a sheathing secured to said material by a nail having its end clinched or turned by said hard strip.

4. In fire-proof shutters and the like, a 100 frame of wood or other material having embedded therein a nail clinching strip, a protective sheathing covering said frame, and panels secured to said frame by nails clinched by the clinching strip, substantially as shown and described.

In testimony whereof I affix my signature in presence of two witnesses.

WILLIAM R. KINNEAR.
